Primary Examiner — Andrew Kerr(74) *Attorney, Agent, or Firm* — Avek IP, LLC(57) **CLAIM**

The ornamental design for a bowl, as shown and described.

DESCRIPTION

FIG. 1 is an isometric view of a bowl according my new design;

FIG. 2 is a first side view of the bowl;

FIG. 3 is a second side view of the bowl;

FIG. 4 is a top view of the bowl; and,

FIG. 5 is a bottom view of the bowl.

Broken lines in the accompanying drawings illustrate unclaimed environmental structure and form no part of the claimed design.

1 Claim, 4 Drawing Sheets(56)
